UNITED STATES PATENT OFFICE

129,010

DESIGN FOR A CATAPULT FOR A BOOMERANG GAME DEVICE OR SIMILAR ARTICLE

Marvin E. Smith, Chicago, Ill.

Application March 24, 1938, Serial No. 76,070

Term of patent 3½ years

To all whom it may concern:

Be it known that I, Marvin E. Smith, a citizen of the United States, residing at Chicago, in the county of Cook and State of Illinois, have invented a new, original, and ornamental Design for a Catapult for a Boomerang Game Device or Similar Article, of which the following is a specification, reference being had to the accompanying drawing, forming part thereof.

The figure is a plan view of a catapult for a

boomerang game device, showing my new design. The article is of no appreciable or substantial thickness.

The reverse side of the article is plain.

I claim:

The ornamental design for a catapult for a boomerang game device or similar article, as shown and described.

MARVIN E. SMITH.
